United States Patent Office

Des. 209,425
Patented Nov. 28, 1967

209,425

INSULATED BOTTLE OR THE LIKE

Robert B. Wells, 11 Woodland Circle,
Carmel, Ind. 46032

Filed Nov. 25, 1966, Ser. No. 4,810

Term of patent 3½ years

(Cl. D58—8)

I claim:

The ornamental design for an insulated bottle or the like, as shown.
